REFLECTOR FOR LAMPS

Friedrich Richard Dietrich, Pasing,
near Munich, GermanyApplication November 20, 1933, Serial No. 698,735
In Germany November 23, 1932

2 Claims. (Cl. 240—41.35)

The invention relates to parabolic reflectors for lamps for vehicles, room lighting, street lighting and other purposes, its object being to provide a reflector which projects, in addition to a parallel beam in the direction of the main axis, deflected beams.

For this purpose rim segments of the reflector are outwardly deflected about the focal point of the parabola. The deflected segments may have parabolic curvatures differing from that of the main parabola, and may be composed of a plurality of bands, deflected to different degrees. It is generally of advantage to use a dispersive glass with the reflector, as will be explained herein-after.

Several examples of reflectors according to the invention are shown in the annexed drawing in which Figs. 1 and 2 are horizontal longitudinal cross-sections of two embodiments of the invention.

Fig. 1 illustrates a parabolic central reflector 1 and two deflected parts 3, at opposite sides of the lamp 2, so that an outwardly deflected beam is projected on both sides in addition to the

beam projected straight ahead by reflector 1. This construction is suitable for vehicles with a single head lamp, and for bicycle lamps.

It is not essential that the parabolic curvature of the deflected portion of the reflector be the same as that of the main portion. Fig. 2 shows a construction with two parts 3 having a shorter focal length than the main part 1.

The reflector may be made in one piece, by means of stamping and appropriate dies. A diffusing glass 5 is mounted on the edge 4 of the reflector to avoid a dark patch between the beams directed straight ahead and to the side.

What I claim is:

1. A reflector consisting of three mutually complementary paraboloid longitudinal sections separated by parallel, vertical planes, said sections having a common focal point, and two of said sections being lateral sections deflected outwardly about said focal point.

2. A reflector according to claim 1, and in which the side portions have a shorter focal length than the central portion.

FRIEDRICH RICHARD DIETRICH.
